C. C. MALTBY & A. DOM.
LOOSE LEAF BINDER.
APPLICATION FILED MAY 28, 1906.

905,726.

Patented Dec. 1, 1908.

UNITED STATES PATENT OFFICE.

CHARLES C. MALTBY, OF CINCINNATI, AND ALEXANDER DOM, OF HARTWELL, OHIO, ASSIGNEES TO THE TWINLOCK COMPANY, OF CINCINNATI, OHIO, A CORPORATION OF OHIO.

LOOSE-LEAF BINDER.

No. 905,726.

Specification of Letters Patent.

Patented Dec. 1, 1908.

Application filed May 28, 1906. Serial No. 319,132.

To all whom it may concern:

Be it known that we, CHARLES C. MALTBY, of Cincinnati, in the county of Hamilton and State of Ohio, and ALEXANDER DOM, of Hartwell, said county and State, both of us citizens of the United States of America, have invented certain new and useful Improvements in Loose-Leaf Binders, of which the following is a specification.

10 This invention relates to certain improvements in loose-leaf binders and has for its object to provide a device of this general character of a simple and inexpensive nature and of a compact, strong and durable 15 construction, which shall be adapted for securely holding the leaves or sheets in position while being capable of convenient and ready actuation to detach such leaves or sheets to permit their removal, substitution 20 or replacement and being also capable of a wide degree of adjustability to accommodate the improved binder for holding a greater or lesser number or thickness of the loose leaves or sheets.

25 The invention consists in certain novel features of the construction and combinations and arrangements of the several parts of the improved loose-leaf binder, whereby certain important advantages are attained and the 30 device is rendered simpler, cheaper and otherwise better adapted and more convenient for use, all as will be hereinafter fully set forth.

The novel features of our invention will be 35 carefully defined in the claims.

In the accompanying drawings which serve to illustrate our invention—Figure 1 is a fragmentary outside elevation of the improved binder embodying our improvements, 40 the sides or covers being thrown out flat laterally and partially broken away (for lack of space) and the back-section being partly broken out at its upper portion to illustrate certain underlying parts, with the operating 45 devices shown in closed position; Fig. 2, a fragmentary view somewhat similar to Fig. 1, but illustrating the interior of the binder-back and covers, certain mechanical parts and contrivances within the lower part of the 50 back-section being omitted to avoid obscuring the underlying devices; Fig. 3, an enlarged view of the devices shown at the lower part of Fig. 2; Fig. 4, a partially dotted diagrammatic view of the link and lever mechanism taken from the upper end of the

binder-back for illustrating the operation of the means for adjusting the lateral-members of the binder-back toward and from each other for use in clamping the loose leaves or sheets at their binding-edges; Fig. 5, a partial section taken longitudinally through one end portion of the binder-back and showing certain features of the adjusting and locking means carried thereby; Fig. 6, an enlarged fragmentary view showing the inner face of one end portion of the central member or back-section of the binder for illustration of the rear cover-plate carried thereby; and, Fig. 7, an end view of said back-section of the binder showing the key opening therein and illustrating the shouldered central projection with which said rear cover-plate is engaged.

As shown in these views, the back of the improved binder is made in sectional form and has a longitudinally-extended central member or back-section 1, the rear or outer surface of which is made rounded or curved to imitate the convexity commonly present in the backs of bound volumes. The back of the improved binder also has or comprises lateral-members formed from metal plates adjustably-held upon opposite lateral edges of the back-section 1 and extended longitudinally along the same. The several members of the binder-back will usually be covered with leather or the like to improve the appearance of the device.

The metal plates of which the lateral members of the binder-back are formed are centrally bent to produce wings or portions 2 and 3 at right-angles to each other, so that each lateral-member has an angular or L-shape in cross-section, and one of the angular wings or portions of each of such lateral-members is extended upon the inner or front surface of the central member 1, (as shown at 3 on the drawings,) and has means for adjusting it in open and closed position upon said central member, while the other angular wing 2 of each of said lateral-members is extended forwardly at right-angles from the plane of said central member 1 and is provided with means comprising telescoping tubular parts or sleeves 5, 5 for detachably-holding the loose leaves or sheets of the binder and means, also, for hinge-connection of the sides or covers 4, 4 of the binder, such hinge-connection being, as herein shown, of such a nature that said sides or covers may

be extended laterally and laid flat in open position to give free access to the contained sheets.

At opposite ends of the binder-back, the 5 lateral-members have telescoping shells or casings 6, 6 of hollow rectangular cross-section serving as substantial end-supports for said lateral-members 2, 3, when adjusted toward and away from each other and, also, 10 adapted for engagement in indentations at the ends of the binding edges of the loose leaves or sheets, in a well-known way, to prevent edgewise movement of said sheets or leaves when clamped between the lateral-members.

The opposite ends of the central member 1 of the binder-back are formed with integral forwardly-directed flanges 7, the joints of said flanges with the convexed rear face of 20 member 1 being made rounded, (as seen in Fig. 5,) so as not to wear the leather-covering or scratch or mar the desk or table at which the binder is used, and on the front surface of said central member 1 at each end 25 thereof are held flat cover-plates 9 and 15, suitably secured to said member and spaced apart sufficiently to allow the free passage back and forth laterally of the inwardly-directed wings or flanges 3, 3 of the respective 30 lateral-members when adjusted toward or from each other, and without the use of any guide-ways whatever. For securing these guide-plates to the member 1, we preferably provide each end flange 7 of said member 35 with a central forward-extension 11 having a straight front edge whereon the end of the corresponding rear cover-plate 9 is securely rested and having shoulders at its ends wherewith are engaged rearwardly-directed 40 ribs or projections 12, 12 integral at opposite edges of said plate 9. Said plates 9 are each formed with lateral arms or lugs 10, 10 held by rivets or the like to member 1, and at their adjacent inner ends, each plate 9, 45 has spaced, rearwardly-directed right-angled arms or lugs 13, 13, also riveted or otherwise fastened to member 1, (as best seen in Fig. 6).

By reason of the rounded or convexed formation of the central member 1 there is produced a chamber therein extended lengthwise behind the rear end-plates 9, 9, and in said chamber is a longitudinally-extended operating-shaft 17, the ends whereof have 50 reverse or right and left-hand screw-threads 18, 18, and one end of which has a squared or otherwise formed portion 19, adjacent to an aperture 8 in one of the end-flanges 7 of member 1, and whereat a key or the like may 55 be inserted for engagement with said squared end 19 to turn the shaft.

16, 16 are bearing-plates held to the arms or lugs 13 of the respective rear plates 9, 9 by means of screws or the like engaging 60 sockets 13^a in said lugs, and wherein the

ends of shaft 17 are adapted to freely turn. These bearing-plates have extensions or wings 24, which are directed along opposite sides of shaft 17 and carry at their ends auxiliary-bearings 25 wherein shaft 17 also 70 turns freely.

The forward cover-plates 15 are held by screws 14 or the like to the front faces of the rear plates 9, 9 at their outer ends, and their opposite inner or adjacent ends are held by 75 means of screws 25^a to the auxiliary-bearings 25, said auxiliary-bearings having central forwardly-extended parts 26 wherewith said screws are engaged. The central or intermediate portion of each forward cover-plate 15 is, of course, spaced in front of the corresponding rear plate 9 to permit the in-turned wings or flanges 3, 3 of the lateral-members to play freely between said plates 80 as above described.

20, 20 indicate nuts or collars provided on the screw rod or shaft 17 outside the respective bearing-plates 16, 16 and 22, 22 are transverse fastening rivets or pins passed through holes made in said nuts and shaft, suitable 90 openings 23, 23 being provided in the central member 1 (as shown in Fig. 5) for affording access to the nuts and shaft in drilling said holes in the proper places and for the convenient insertion of said rivets or pins. Tool-engaging notches 21 are cut in the collars 20, to aid in initially turning the latter up to place against the plates 16 at the time the lateral-members are closed (as in Fig. 1) and the said shaft then assumes its proper position and relation in the binder to receive the pins 22 that prevent its lengthwise-movement.

27, 27 are nuts or travelers having threaded-engagement on the respective, oppositely 105 screw-threaded end portions 18 of shaft 17, and each such nut has opposite, lateral projections 28, 28 whereon are pivotally-attached the inner ends of oppositely-inclined levers 29, 29 whose outer ends are pivotally-connected as shown at 30, 30 with the inwardly-directed wings or flanges 3, 3 of the respective lateral-members of the binder-back. Links 31, 31 with inner ends pivotally-connected at 28^c, 28^c on the bearing-plate 115 extensions 24, have their outer ends pivotally-connected with the central portions of the respective levers 29, 29 to form movable fulcra therefor.

The arrangement of links and levers at the 120 opposite ends of the binder-back is reversed to afford connection of the outer ends of levers 29 with the lateral-members at points as near the ends of said lateral-members as required for clamping the sheets between 125 said lateral-members, and owing to the presence of the reverse-threads 18, it follows that when the shaft is turned in one direction, said lateral-members are evenly and uniformly drawn together to forcibly clamp and 130

securely hold the binding edges of the loose leaves or sheets, and when said shaft is reversely turned, said lateral-members of the binder-back are moved apart from each other so as to relax pressure on the leaves or sheets and permit the same to be removed and inserted at will. Since the shaft 17 is securely held against endwise movement by the contact of its locked collars or nuts 20, 20, with the bearing-plates 16, 16, it is evident that the lateral-members are held in true and exact parallelism during adjustment toward and from each other, and a uniform and direct pressure is exerted on the binding edges of the loose leaves or sheets without providing any extraneous guiding means.

The partially dotted diographic view, Fig. 4, best illustrates the operation of the link and lever arrangement taken from the upper end of the binder-back, the closed position of such link and lever mechanism for use in operating the lateral-members of the binder being represented by the full lines *a*, *a*, while the open position of said link and lever mechanism, to relax pressure of the lateral-members and permit free removal or like insertion of the loose leaves or sheets, is represented by the diagonal dotted-lines at *b*, *b*. The several pairs of longitudinally-movable pivotal-points 28, 28 are initially placed at the same immovable distance apart, transversely of the back, as that of the several pairs of transversely-immovable pivotal-points 28^c, 28^c and are maintained in a rectangular relation to each other at all times during the action of transversely-reciprocating the lateral-members of the binder-back, toward and from each other (as best seen along the parallel dotted-lines 28^d, 28^d in said diagram, Fig. 4).

In practice, the length of each of the links 31, 31 between pivotal-centers is exactly half that of the length between pivotal-centers of the respective levers 29, 29, and the action resultant therefrom is such that the pivotal-points 28, 28 move in a true straight line longitudinally or vertically while the pivotal-points 30, 30 move in a true straight line laterally or transversely, the respective linear movements of both sets of said pivotal-points being always at right-angles to each other and thus the reciprocal sidewise-movements of the lateral-members carrying the hinged sides or covers 4, 4 are maintained in an absolutely straight line, without any strain whatever on the link and lever mechanism and without the use or presence of guides or guide-ways of any kind being necessary.

The improved binder constructed as above described is not merely of an extremely simple and inexpensive nature, but is especially desirable for use by reason of the parallel movement of the lateral-members assured without

the employment of extraneous guiding means by simply holding shaft 17 from longitudinal-movement, whereby uneven movement or sticking of the lateral-members is absolutely prevented in the adjustment thereof toward and from each other to clamp or release the leaves or sheets, and it will also be obvious, from the above description of our improvement, that the improved binder is capable of considerable change without material departure from the principles and spirit of the invention and for this reason we do not desire to be understood as limiting ourselves to the precise form and arrangement of the several parts of the device herein set forth in carrying out our invention in practice.

We claim—

1. In a loose leaf binder the combination of leaf clamping members supported to reciprocate, means for reciprocating said clamping members comprising a screw shaft having oppositely threaded portions, nuts traveling thereon, fixed bearing plates in which said shaft is journaled, toggle levers connected to the clamping members and movable fulcrum members extending from said bearing plates and supporting said toggle levers intermediate their ends.

2. In a loose-leaf binder, the combination of a central back-member having inwardly directed end flanges provided with raised or extended portions the opposite ends of which latter produce shoulders and the rear cover-plates held to said central member with their outer edges resting on the edges of said end flanges and having lateral, rearwardly-directed projections engaged on the shoulders of said end flanges.

3. The combination of the central member, bearing-plates carried thereby, a screw-shaft journaled in the bearing-plates, nuts having threaded-engagement with the screw-shaft, lateral-members movable toward and from each other, lever-mechanism affording connection between the nuts and said lateral-members, and collars held on said shaft outside of the bearing-plates for engagement therewith to prevent endwise movement of the shaft.

4. In a loose leaf binder, the combination of leaf clamping members supported to reciprocate, and means to reciprocate said members comprising a screw shaft, a nut traveling thereon, toggle levers connecting the clamping members and nut, and movable fulcrum members supporting the toggle levers intermediate their lengths.

5. In a loose leaf binder, the combination of leaf clamping members, guides upon which said members are supported to reciprocate toward and from each other, and mechanism to actuate said clamping members comprising a screw shaft journaled to extend with its axis perpendicular to the direction of movement of the clamping members and

confined against endwise movement, a pair of nuts traveling thereon, toggle levers connecting said clamping members with said nuts, and pivoted fulcrum links connecting the central portions of the respective toggle levers with relatively fixed points of support.

6. In a loose leaf binder, the combination of a back member and a pair of opposed clamping members mounted to reciprocate toward each other and relatively across said back member, a right and left threaded screw shaft journaled upon the back member to extend longitudinally of the latter and confined against endwise movement, traveling nuts upon the respective threads of said shaft, toggle levers connecting each nut with each clamping member, a fulcrum link connecting the intermediate portion of each toggle lever with a fixed support upon said back member.

7. In a loose leaf binder, the combination of a back member and a pair of opposed clamping members mounted to reciprocate toward each other and relatively across said back member, a right and left threaded screw shaft journaled upon the back member to extend longitudinally of the latter and confined against endwise movement, traveling nuts upon the respective threads of said shaft, toggle levers connecting each nut with each clamping member, a fulcrum link connecting the intermediate portion of each toggle lever with a fixed support upon said back member, and impaling devices mounted upon the respective clamping members.

8. In a loose leaf binder, the combination of a back member, a pair of clamping members each provided with impaling devices, the impaling devices of the two clamping members having telescopic sliding engagement with each other, and means for actuating said clamping members comprising a right and left threaded screw shaft journaled upon the back member midway of the dis-

tance between the clamping members and 45 parallel with the clamping faces of the latter, nuts upon the respective threaded portions of said screw shaft, uniform length symmetrically disposed toggle levers connecting each traveling nut with each clamping member, 50 and uniform length symmetrically disposed fulcrum links connecting the intermediate portions of each toggle lever with fixed pivot supports upon the back member.

9. In a loose leaf binder, the combination 55 of a back member, a pair of clamping members each provided with impaling devices, the impaling devices of the two clamping members having telescopic sliding engagement with each other, and means for actuating said clamping members comprising a right and left threaded screw shaft journaled upon the back member midway of the distance between the clamping members and parallel with the clamping faces of the latter, 60 nuts upon the respective threaded portions of said screw shaft, uniform length symmetrically disposed toggle levers connecting each traveling nut with each clamping member, and uniform length symmetrically disposed 65 fulcrum links connecting the intermediate portions of each toggle lever with fixed pivot supports upon the back member, said fulcrum links being each of a length equal to one-half the length of the lever with which 70 it is connected and the fixed pivotal supports of said fulcrum links being arranged in alignment with the pivotal supports of the actuating nuts with which the corresponding 75 toggle levers are connected.

Signed at Cincinnati, Ohio, this 17th day of May 1906.

CHARLES C. MALTBY.
